(57) **CLAIM**

The ornamental design for a rectangular perforated pan, as shown and described.

DESCRIPTION

FIG. 1 is a perspective view from the top of the rectangular perforated pan;

FIG. 2 is a front view thereof;

FIG. 3 is a back view thereof;

FIG. 4 is a right side view thereof;

FIG. 5 is a left side view thereof;

FIG. 6 is a top view thereof; and

FIG. 7 is a bottom view thereof;

FIG. 8 is a perspective view from the bottom thereof;

FIG. 9 is a perspective view from the top of a second embodiment of the rectangular perforated pan;

FIG. 10 is a front view thereof;

FIG. 11 is a back view thereof;

FIG. 12 is a right side view thereof;

FIG. 13 is a left side view thereof;

FIG. 14 is a top view thereof;

FIG. 15 is a bottom view thereof; and,

FIG. 16 is a perspective view from the bottom thereof.

FIGS. 9 through 16 are shown broken apart to indicate indeterminate dimensions.

1 Claim, 10 Drawing Sheets
